UNITED STATES PATENT OFFICE.

EMIL E. NOVOTNY, OF PHILADELPHIA, PENNSYLVANIA, ASSIGNOR TO JOHN STOGDELL
STOKES, OF PHILADELPHIA, PENNSYLVANIA.

MANUFACTURE OF PRINTING-PLATE MATRICES.

1,410,031.

Specification of Letters Patent. Patented Mar. 21, 1922.

Application filed July 18, 1921. Serial No. 485,728.

To all whom it may concern:

Be it known that I, EMIL E. Novotny, a citizen of the United States, and resident of Logan, Philadelphia, in the county of Philadelphia and State of Pennsylvania, have invented certain new and useful Improvements in Manufacture of Printing-Plate Matrices, of which the following is a specification.

This invention relates to matrices and the method of manufacturing the same.

In the present instance I have shown and described my invention as used for making matrices designed for the production of printing plates, but I wish it to be understood that it is not limited in its useful application to this particular purpose. For example, by the practice of my invention, matrices for the production of numerous other regular and irregular shapes and articles may be made.

In the production of a matrix according to my invention, I subject the original article to be reproduced, such for example as an original printing plate, type form, etching or the like, to relatively light pressure against a plastic or pasty body of metal, preferably an alloy of a low melting point, this body of metal being cooled and hardened while the original is in contact therewith so as to produce a matrix which will exhibit and define the exact details of the original and which may be readily separated from the latter.

Briefly, in the practice of my invention, I may proceed in several ways. For example, I may select a body of metal, such as an alloy composed of lead, tin and bismuth, which will have a relatively low melting point, and subject this to the action of heat until the alloy is partially melted or fused, or assumes a pasty or mushy, plastic condition, the alloy, however, not being heated to the point where it is in a free-flowing, fluid-like molten condition. When the body of metallic alloy is in this pastelike, partially melted or plastic condition I place thereagainst the original to be reproduced, and subject the two contacting elements to exceedingly light pressure to sink or press the original into the metal, at the same time cooling the latter to bring it to its original hard condition. After the metal has hardened, the pressure may be relieved and the original readily removed, particularly if a suitable separating agent be used.

Or, if desired, in the practice of my in-

vention, I may subject the body of metal, such as the low melting alloy, to the action of heat until the metal is completely melted or is in a fluid-like, free-flowing state. Upon the surface of the bath of molten metal I deposit an oily substance, such as paraffin, for the purpose of preventing oxidation, and also to act as a separating agent to permit the ready removal of the original after the matrix has been formed. Upon this coated molten path I then place the original to be reproduced, the faces of the latter being preferably coated first with an oxidizing agent, such as a weak solution of tincture of iodine, or pyrogallic acid, and then with a thin layer of polished graphite. I then subject this original to pressure, preferably air pressure, in a suitable press, at the same time cooling and hardening the body of metal, suitable bearers being provided to limit the depth into which the original may sink into the bath, suitable side bars also being provided to limit the depth of the metal bath, or to insure that any excess of metal forced upward by displacement, may flow away over these side bars.

In the accompanying drawings:

Figure 1, is a view in end elevation of a slab of metal, such as a low melting alloy which may be used in the making of the matrix.

Figure 2, is a cross sectional view of the slab receiving pan.

Figure 3, is a view partly in section and partly in elevation of the conventional type form equipped with bearers for limiting the depth of penetration of the type form into the softened or plastic body of metal.

Figure 4, is a view showing conventionally the platens of a press and illustrating the manner of forming the matrix by immersing the type form in a bath of molten metal and subjecting the same to pressure and cooling by the action of air.

Figure 5, is a view illustrating conventionally another arrangement of press and showing the manner of making the matrix by subjecting the type form to mechanical pressure while in contact with a pasty or partially melted or fused body of metal.

Figures 6, 7 and 8, are cross sectional views illustrating forms of matrices which may be made by the practice of my invention.

I will first describe the manner of making a matrix by immersing a type form in

a molten bath of metal and subjecting the same to pressure and cooling and hardening under the action of air, and in this connection particular reference is made to Figures 5 1 to 4 inclusive.

- In carrying out my invention, I select a suitable metal having the desired melting point and the ability to assume a pasty or plastic condition before setting to its final 10 hard form, my preference being an alloy consisting of six parts of lead, six parts of tin and one part of bismuth, by weight. Such an alloy has a melting point of about 327° F. This metallic alloy, which may be 15 in the form of a slab such as is shown at 1 in Figure 1, may be melted down in a suitable container, and when the matrix is to be made such molten metal may be run or poured into the pan 2, shown in Figure 2. 20 If any make-ready is to be incorporated in the printing plate, such make-ready, shown at 3, may be placed on the bottom of the pan 2 before the metal is poured or run into the pan. The pan is preferably provided with 25 over-flow bars 4, so that when the type form enters into the molten metal the surplus metal displaced will flow over the top edges of these bars and into the gutters 5 formed by the bars 4 and the sides 6 of the pan. 30 The original to be reproduced, in the present instance a type form, is indicated as an entirety by the letter T and embodies a combination of half tone and type locked in the usual chase 7, the form also embracing, however, the immersion limiting bearers 8 which are slightly greater than the type high so that when the type form is reversed and placed in the molten bath as shown in Figure 4 the projecting ends of 35 40 the bearers will extend through the bath of metal and rest upon the floor of the pan, thereby limiting the distance of penetration of the type body itself into the body of the metal. In the making of the matrix I 45 also preferably employ a press conventionally shown at P, this press including the top platen 9 and the lower platen 10. This lower platen is provided with channels 11 for the passage of a heating agent, such as 50 steam, while the top platen 9 is provided with an inlet 12 for the admission of cold air under pressure, an outlet 13 for the exit of heated or waste air from the platen and a vacuum outlet 14 which may be used when 55 60 it is desired to reduce the amount of air in the chamber of the press. The press is also provided with side bearer bars 15 equipped with suitable packing 16 so that when the press is closed, an air-tight chamber 17 will 65 70 be formed. The air inlet 12 is preferably provided with a pulsating valve 19, while the air outlet 13 is provided with a bleed valve 20 and the exhaust outlet 14 is provided with an ordinary globe valve 21, these 75 80 valves being conventionally indicated as

they may be of any ordinary or approved form. The bottom platen 10 is provided with a valved steam inlet pipe 22 and a steam exhaust pipe 23 which leads to a suitable trap (not shown).

70

In making the matrix the type section of the type form T is preferably provided with a very thin electrolytic film, produced by treating the form in a shallow electrolytic bath, the electrolytic material, however, being confined to the type and half tone section of the form. This coating is shown at 24. The form thus coated is then treated to another coating of an oxidizing agent such as a weak solution of tincture of iodine 80 or pyrogallic acid, and is then treated to a third coating or surface coating of graphite, although this is not essential, but the graphite will assist in the ready separation of the type form from the bath, while the 85 electrolytic and iodine coatings will prevent the amalgamation of the molten metal with the type metal.

75

A slab 1 of the alloy of suitable dimensions having been melted down and run into the pan, the latter is placed upon the bottom platen of the press as shown in Figure 4, said bottom platen being heated at this time by the passage of steam therethrough, the heat of the steam keeping the 90 alloy in a fluid-like or molten condition until the press is closed and the matrix making operation is in progress. Before placing the pan with the molten metal in the press, I preferably place upon the surface of the 95 metal an oily substance, such as paraffin, which prevents the formation of oxides upon the surface of the bath, it also assists in the subsequent separation of the original type form from the hardened matrix. The type 100 form T prepared as heretofore described is now inverted or placed face down in the molten bath, the depth of immersion or penetration of the type form into the bath being 105 limited by the bearers 8 of the type form 110 which project through the molten mass and rest upon the bottom of the pan. These bearers are of such height, however, as to permit the entire face section of the type form to be immersed in the bath to the desired depth. The press is now closed to form 115 an air-tight chamber within which the pan and the immersed type form are located. The heating steam may now be cut off, and the vacuum valve being closed, because the 120 vacuum is not used in this instance, the outlet valve 20 of the air outlet 13 is opened and air under pressure is forced in waves or pulsations through the air inlet 12 into the chamber, this pulsating or wave-like effect 125 being due to the pulsating valve 19 which opens and closes as is usual in valves of this type. The result will be that the cool air, flowing in pulsations into the chamber will drive the warm air out through the pipe 13, 130

and such cool air at the same time coming in pulsations as it does will not only cool or set the body of metal, first to a pasty or plastic condition and then to its final or 5 hard condition, but will punch or compact the gradually cooling and solidifying metal up against and into intimate contact with every portion of the area of the type face immersed in the metal. This pulsating ad- 10 mission of the air may be continued for a suitable period, say for about two minutes, at the end of which time the metal will be sufficiently solidified or hardened as to have assumed a rigid condition, and the 15 matrix will have been produced with the greatest detail with relation to the contacting face of the type form. The air may now be cut off from the air inlet 12 and the press opened and the pan with the now so- 20 lidified matrix and the type form may be lifted out and the type form removed. The latter may be readily accomplished, as owing to the layer of paraffin which has been placed upon the metal, and the coatings on 25 the face of the type form, ready separation is obtained. The metal matrix will not stick to the pan because the latter is made of ordinary steel which has no affinity for an alloy of the character I use.

30 In some instances, instead of first melting down the alloy slab 1 and running it in molten form into the pan, I may place the slab in the pan, apply the paraffin to the face of the slab, and then place the inverted 35 type form in position on the slab and close the press. The melting down of the slab in this case will be accomplished by the steam passing through the lower platen of the press, but before so melting down the slab, 40 but while the press is closed, the exhaust valve 21 of the vacuum outlet 14 may be opened and vacuum applied to the outlet 14 to draw from the closed chamber and from the spaces between the type, as much air as possible. The melting down of the slab may now take place, the vacuum closed or cut off, and the admission of cold air pressure and the exhaustion of the hot air accom- 45 plished as heretofore described to form the matrix, after the type form has sunk or imbedded itself by graphite into the fused or melted slab.

In Figure 5 I have shown a modified arrangement for making the matrix.

In this case the numeral 30 indicates the lower, vertically moving platen of the press, while 31 is an upper stationary platen, preferably provided with a steam inlet 32, and a steam outlet 33, so that the platen may be heated if desired. This upper platen carries at one side a stationary type form clamping bar 34 and at the opposite side a shifting or movable type form clamping bar 35, the latter being shifted in any well-known manner as by means of the rotatable screw 36

upon which travels the threaded sleeve 37 carrying clamping bar 35, suitable hand wheel 38 being provided for rotating the screw. The type form T' which may or may not have its face coated with the separating 70 medium as aforescribed is clamped between the clamping bars 34 and 35 as shown and is therefore held suspended at the under side of the upper platen of the press as shown. Upon the lower platen of the press 75 is placed a base-board 38' of asbestos or other non-conducting material, and upon this base-board rests a shallow pan 39, in which has been placed a bath of the molten metal, the surface of the bath having had the paraffin 80 placed thereon as before mentioned. This lower vertically moving platen is provided with a side bearer bar 40 which is adopted to contact with the stationary clamp 34 when press is closed, while the upper platen of the 85 press carries a bearer bar 41 adapted to contact with the lower platen of the press when the press is closed.

When the pan with the bath of molten metal is placed in the press, the latter re- 90 mains open until the metal has partially solidified or cooled and has assumed a pasty, plastic condition. At this stage the press may be closed and the matrix molded, in this instance, however, air pressure not being 95 used, as the pressure exerted in making the matrix is entirely mechanical and is accomplished by the vertical movement or closing action of the lower platen, which forces the plastic or pasty mass upward and into contact with the face of the type form, the depth of penetration being, of course, limited by the side bearers. The press remains closed for about half a minute which is sufficient to permit the cooling and solidifying of the 105 metal. Of course, during this cooling or solidifying of the metal, the steam has been cut off from the upper platen, and if desired, cold air or water may be admitted in the place thereof, obviously thus assisting in 110 cooling or chilling the metallic mass.

The press may then be opened and the matrix with the pan removed.

In this connection it is to be understood that instead of completely melting down the 115 metallic alloy, until it assumes a fluid-like or flowing condition, the molding may take place after the alloy has been heated sufficiently to reduce it to a pasty or plastic mass, but not a fluid state.

In Figure 6 I have shown at M an all-alloy matrix made in the ways hereinbefore described, while in Figure 7 I have shown at M' a modified form of matrix comprising a body section m of the alloy and a facing section m' 125 thereof formed of a layer of foils, such as a foil composed of equal proportions of tin and lead, which has been rolled in or impressed upon the type form prior to the making of the matrix, and which has adhered 130

to the matrix body during the molding operation.

In Figure 8 the modified form of matrix shown at M^2 is composed of an alloyed body m^2 faced with an electrolytic coating m^3 which was deposited upon the outer face of the type form prior to the molding of the matrix or which might be deposited upon the alloyed matrix body m^2 itself after the matrix was formed.

Matrices made in accordance with my invention may be produced with a very light, or minimum amount of pressure, and therefore will not damage soft, original type made during the making, but when in their cooled and set form such matrices are capable of withstanding rough usage, therefore enabling a large number of reproductions to be economically made therefrom. Such matrices may also be used for the reproduction of plates and the like by electrolytic methods, either by being subjected to a spray, or bath, or may be employed for molding plates made from such materials as synthetic resins, shellacs, asphaltum and similar plastic substances. Furthermore, by my method, in addition to obviating the disadvantages of expense and injury due to cold lead molding processes, I am enabled to accomplish a purpose heretofore unattainable, that is the making of matrices against type and with the use of molten metal. As is well-known, it is out of question to pour molten metal on a type form for, because of the depth of the form, the metal will flow into the deep, hollow portions, thereby producing a matrix of such severe depth as to be worthless for practical purposes.

In addition, such action would cause the matrix to lock with the type so that it could not be removed therefrom unless the entire type form was taken apart, which, of course would not be practicable from a commercial standpoint.

It will, of course, be understood that instead of using ordinary or relief type for producing a matrix, I may employ intaglio forms, such as matrices, as the original to be used in making metallic relief plates by this method.

While I have herein shown and described certain preferred embodiments of my invention, I wish it to be understood that I do not confine myself to all the precise details herein set forth, as modification and variation may be made without departing from the spirit of the invention or exceeding the scope of the appended claims.

What I claim is:

1. The herein described method of making a metallic matrix which consists in preparing a body of metal so that at one stage it is in a mushy, pasty condition, and subjecting the metal to simultaneous pressure and cool-

ing, while the metal is in said condition and in contact with the original to be reproduced, to form a hard and set matrix having a molding face complementary to the contacting face of the original.

2. The herein described method of making a metallic matrix which comprises placing an original to be reproduced in proper relation to a body of metallic matrix forming material, while using a separating medium between the two, and, while the metal is in a pasty or mushy stage, simultaneously using positive pressure and cooling for a relatively short period of time to form the matrix face by contact with the original, and at the same time to rapidly set and cool the matrix, and then stripping such matrix from the original.

3. The herein described method of making a metallic matrix which comprises mounting an original to be reproduced in a suitable supporting device whereby said original is held in proper relation to a body of metallic matrix forming material, and, while the metal is in a pasty or mushy state, simultaneously using positive pressure and cooling to form the matrix face by contact with the original and at the same time set and cool the matrix, and then stripping such matrix from the original.

4. The herein described method of making a metallic printing plate matrix which comprises placing an original printing element to be reproduced in proper relation to a body of suitably supported and confined metallic matrix forming material, and, while the metal is in a pasty or mushy stage, simultaneously using positive pressure and cooling for a relatively short period of time, to form the matrix face by contact with the original printing element and at the same time to rapidly set and cool the matrix, and then stripping said matrix from the original printing element.

5. The herein described method of making a metallic printing plate matrix, which comprises placing an original printing element to be reproduced in proper relation to a body of suitably supported and confined metallic matrix forming material, and while the metal is in a pasty or mushy stage, simultaneously using, for a relatively short period of time, positive pressure and cooling to cause the penetration of the original printing element into the metallic matrix forming material for a predetermined depth, to rapidly form the matrix face and at the same time quickly set and cool the matrix, and then stripping said matrix from the original printing element.

6. The herein described method of making a metallic matrix which comprises mounting an original to be reproduced in suitable supporting means located in proper relation to

a body of metallic matrix forming material placed in a suitably supported and confined structure which is supported upon a body of non-heat conducting material, and, while 5 the metal is in a pasty or mushy stage, simultaneously using positive pressure and cooling to form the matrix face by contact with the original, and at the same time set

and cool the matrix, and then stripping such matrix from the original.

Signed at Summerdale, Philadelphia, in the county of Philadelphia and State of Pennsylvania this 8th day of July, A. D. 1921.

EMIL E. NOVOTNY.
